UNITED STATES PATENT OFFICE.

EDWARD NELSON, OF JERSEY CITY, NEW JERSEY.

AUTOMATIC SIGNALING DEVICE FOR MARINE VESSELS.

1,194,770.

Specification of Letters Patent. Patented Aug. 15, 1916.

Application filed August 9, 1915. Serial No. 44,554.

To all whom it may concern:

Be it known that I, EDWARD NELSON, a citizen of the United States, residing at Jersey City, in the county of Hudson and State 5 of New Jersey, have invented certain new and useful Improvements in Automatic Signaling Devices for Marine Vessels, of which the following is a specification.

This invention comprehends certain new 10 and useful improvements in signaling devices for submarine vessels, and has for its primary object, the provision of a signaling device which will be especially adapted for submarines and the like.

15 The invention has for another object, the provision of a signaling device of this character which will be automatically operated to signal to passing vessels should the vessels carrying the signaling device be in distress beneath the surface.

20 The invention has for a further object, the provision of an automatic signaling device of this character which will be of improved and novel construction and operation and which may be readily installed in submarines or other vessels.

A still further object of the invention resides in the provision of an automatic signaling device of this character which will 25 be of such construction that, if desired, it may be manually operated and will be of such construction as to afford communication between the passengers of the vessel in distress and parties upon a rescuing vessel.

30 With the above and other objects in view the invention resides in the novel construction, combination, and arrangement of parts as hereinafter set forth in the specification and pointed out in the claims and shown in 35 the accompanying drawings, in which—

Figure 1 is an elevation of the complete device showing the same as constructed for installation upon a submarine or the like. Fig. 2 is a top plan view of the same. Fig. 45 3 is a detail elevation of a slightly modified form of the normally closed float case. Fig. 4 is an elevation at right angles to Fig. 3. Fig. 5 is a plan view of the modified form of float case showing the same in open 50 position.

Referring more particularly to the drawings in which similar reference characters designate corresponding parts throughout the several views, 1 designates a portion of 55 the deck of the submarine or similar vessel

having depending from its under face a bracket 2 upon which is pivoted, as shown at 3, a spring controlled locking trigger 4 to one arm of which is connected a flexible connecting member 5 which is also connected 60 with a small float 6 and passes through a guide arm 7 depending from the deck 1. Resting upon the opposite arm of the spring controlled locking trigger 4 is one end of the long weight carrying arm 8 radiating from 65 the hub 9 which also carries a short radial arm 10 projecting from its opposite side and provided in its upper face and adjacent its free end with a guide groove 11, the purpose of which will presently appear. The hub 70 9 has also formed therewith a segmental gear 12 and is mounted for rotation upon the stationary shaft 13.

The spring controlled locking trigger 4 serves to normally retain the long weight 75 carrying arm in its uppermost unoperated position. Should the trigger be operated manually, however, or by an upward movement of the small float 6 owing to water reaching the same, the spring controlled 80 locking trigger 4 will be drawn away from beneath the free end of the long weight carrying arm 8 and the latter will be caused, by the weight 14 mounted thereon and connected by a flexible member 15, such as a 85 chain, to the under face of the deck 1, to swing downwardly, thereby rotating the hub 9 and forcing the arm 10 upwardly and at the same time rotating the segmental gear wheel 12 which is in mesh with the gear 16 90 mounted upon the lower end of the vertical shaft 17. This will cause rotation of the vertical shaft 17 which is suitably mounted for rotation, as shown at 18, in an inverted bearing member 19 secured by suitable securing 95 members 20 to the upper face of the deck 1. The securing members 20 also pass through a suitable bearing plate 21 to secure the same against the under face of the deck 1 around the vertical shaft 17. A suitable 100 bearing nut 22 having a packing 23 therein for the vertical shaft 17 is secured to the bearing plate 21, as shown at 24. The vertical shaft 17 has a pinion 25 mounted upon its upper extremity and engaged with the 105 teeth 26 on one face of the reciprocating bar 27 which is slidably engaged through the guide bracket 28 mounted upon the bearing member 19. The reciprocating bar 27 is secured upon the slide plate 29 which closes 110

and forms the top of the float case 30, said slide plate 29 engaging in the channel 31 formed adjacent the upper edge of the upper section of the float case secured upon the upper face of the deck 1, by suitable securing members 32 passing through the flanged lower edge 33 of said upper portion of the float case 30. The securing members 32 also pass through the deck 1 and through the upper flanged edge 34 of the lower portion 35 of the float case 30, said lower portion 35 being secured to the under face of the deck 1.

The normally closed water conducting pipe 36 has one end extending through the deck 1 while its opposite end is secured in the lower portion 35 of the float case 30 and this water conducting pipe 36 is normally closed by a suitable valve 37 positioned therein and having a valve opening arm 38 extending therefrom with the free end thereof resting in the guide groove 11 of the short arm 10, the valve 37 being of the automatic closing type.

Upon downward movement of the long weight carrying arm 8 and upward movement of the short arm 10 under influence of the weight 14, the free end of the valve opening arm 38 will ride in the guide groove 11 and thereby open the valve 37 to allow passage of water from above the deck 1 to the interior of the lower portion 35 of the float case 30, below the signaling float 39 positioned in said float case 30 and preferably provided with an annular flange 40 resting upon the seat 41 provided therefor by extending the deck into the float case 30 for a short distance, it being understood that the signaling float 39 extends above and below the deck 1, as clearly shown in Fig. 1 of the drawings.

As the water enters the lower portion 35 of the float case 30 beneath the signaling float 39, and the plate 27 is withdrawn from the top of said float case 30, the signaling float 39 rises automatically until it reaches the surface of the water, the pivoted signaling flag 41 secured to the top of the signaling float 39 in any suitable manner as shown at 42 being swung to upright position, under influence of the spring 43 secured thereto and to the signaling float 39. It will be understood that while the signaling float 39 is in position within the float case 30, the signaling flag 41 is pressed downwardly against the tension of the spring 43, by the plate 29.

Secured in the eye 44 at the small lower end of the signaling float 39 is one end of a cable 45 which is normally coiled upon the removable bottom 46 of the lower portion 35 of the float case 30 and secured to the same in any suitable manner not shown. The cable 45 may be of any desired size and preferably

has secured therein current conducting wires 65 47 leading from a telephone 48 within the vessel and extending into the signaling float 39 and connected with and terminating at the binding posts 49 in the upper portion of the signaling float 39, whereby the telephone 70 48 may be electrically connected with a telephone carried upon a rescuing vessel in order that the persons upon the latter may communicate with the parties within the vessel in distress. It will also be evident that 75 should the cable 45 be of sufficient size and strength, it may also be employed for assisting in raising the vessel to the surface.

In Figs. 3, 4, and 5 I have shown a modified form of the upper portion of the signaling float case and in this form said upper portion is composed of two sections 49 and 50 with curved or convex upper portions, the sections 49 and 50 being adapted to slide upon the oppositely flanged guide plate 51 85 toward and away from one another to close and open the float case. The guide plate 51 has longitudinal guide flanges 52 formed on its opposite edges with bearing brackets 53 mounted thereon and serving to support the 90 stub shafts 54 which carry the operating arms 55 having oppositely extended short arms 56 secured to their free extremities and pivoted to the upper float case sections 49 and 50, whereby rotation of the stub shaft 54 95 in one direction will force apart said sections 49 and 50 to permit the signaling float 39 to rise from within the float case. Rotation of the stub shafts 54 in the reverse direction will swing the operating arms 55 in the opposite direction and cause the short arms 56 to draw together the upper float case sections 49 and 50, thereby securely closing the float case and covering and protecting the signaling float 39, water being prevented 105 from passing between the meeting edges of the upper float case sections 49 and 50 by the flange 57 carried by one of said upper float case sections and fastened beneath the opposite upper float case section when said sections are in closed position.

Rotation of the stub shafts 54 in either direction is controlled by the reciprocating bar 27 which, in this form of the device, is pivoted to one of the upper float case sections, in any suitable manner as shown at 58.

From the foregoing it will be readily seen that this signaling mechanism may be operated at any time desired by a party within the vessel by simply raising the locking trigger 4 to release the long weight carrying arm 8. It will also be evident that should any accident happen to the vessel and especially when the vessel is of the submarine type and traveling below the water surface, water 125 entering the vessel and reaching the small float 6, the latter will rise automatically and raise the locking trigger 4, thereby auto-

matically releasing the long weight carrying arm 8 and starting operation of the signaling mechanism.

While the preferred embodiments of the invention have been clearly shown, it will be understood that minor changes in the details of construction, and arrangement of parts may be resorted to within the scope of the appended claims without departing from the spirit of the invention or sacrificing any of the advantages of the same.

What is claimed is:

1. A signaling device of the class described comprising a float case, a float within said float case, a cable connected with said float and with said float case, means for automatically opening said float case, and means operated by the last-mentioned means for permitting entrance of water to said float case beneath said float.

2. A signaling device of the class described comprising a float case, a float within said float case, means for connecting said float with said float case, a water conducting pipe leading to the interior of said float case beneath said float, a valve within said water conducting pipe, means for opening the upper portion of said float case, and means controlled by the last-mentioned means for opening said valve to permit water to enter said float case beneath said float and raise the latter.

3. A signaling device of the class described comprising the combination with a vessel deck; of a float case extending through said deck, a float within said float case, a cable connected with said float and with the float case, a slide bar, a weight carrying arm, operable connections between said weight carrying arm and said slide bar, means for normally retaining said slide bar in unoperated position, said weight carrying bar being adapted when released to operate the slide bar and thereby open the case, and means for permitting entrance of water to the float case below the float upon opening of said float case.

4. A signaling device of the class described comprising the combination with a vessel; of a float case carried thereby, a float within said float case, a stationary shaft, a hub mounted for rotation upon said stationary shaft, a rotary shaft, operative connections between said hub and said rotary shaft, a slide bar, means for operating said slide bar from said rotary shaft, means for supporting said rotary shaft, a locking trigger, a weight carrying arm projecting from said hub and resting upon said locking trigger, a weight mounted upon said weight carrying arm causing outward movement of the latter upon movement of the locking trigger to inoperative position, a trigger operating float connected with said locking trig-

ger, said weight being connected with said vessel to limit downward movement of said weight carrying arm, downward movement of said weight carrying arm causing operation of the slide bar in one direction to open the float case, and means for permitting entrance of water to said float case beneath said float to raise the latter.

5. A signaling device of the class described, comprising a normally closed float case, a float within said float case, a slide bar, means for operating said slide bar to open the upper portion of said float case, means for locking the last-mentioned means against operation, a float connected with the locking means, and means for permitting the entrance of water to said float case beneath said float upon operation of the slide bar.

6. A signaling device of the class described comprising a float case, a signaling float within said float case, a plate for closing the top of said float case, a slide bar connected with said plate, means for operating said slide bar to withdraw said plate, means for causing the operation of the last-mentioned means and permitting entrance of water to said float case beneath said float upon withdrawal of said plate, and means for connecting said signaling float with said float case.

7. A signaling device of the class described comprising a float case having its upper portion formed in sections, a signaling float within said float case, a cable within said float case and connected with the latter and with said signaling float, means for moving the sections of said float case toward and away from one another, means for locking the last-mentioned means against operation, releasing means for the locking means, and means for permitting the entrance of a fluid into said float case to force the float out of the same upon separation of said float case sections.

8. A signaling device of the class described comprising a float case, a float within said float case, a normally closed fluid conducting member connected with said float case, and co-operating means for simultaneously opening said float case and said fluid conducting member.

9. A signaling device of the class described comprising a float, a case for said float, a slide cover for said case, a lever, means tending to rock said lever, a latch member for holding said lever from rocking, and means actuated by the rocking of said lever for withdrawing said slide cover from said case.

10. A signaling device of the class described comprising a float, a case for said float, said case being formed of a pair of sliding sections, an operating lever, means

connected to one of said sections controlled by said operating lever for sliding said section, toggle links between said sections to give movement to the second section, and 5 means for normally locking said lever in inoperative position.

11. A signaling device of the class described comprising a float, a case for said float, said case being formed of a pair of 10 sliding sections, an operating lever, means connected to one of said sections and controlled by said operating lever for sliding said sections, toggle links between said sec-

tions to give movement to the second section, means for normally locking said lever in inoperative position, means for conveying a fluid to the float case beneath said float, and means actuated by said operating lever for controlling the flow of fluid through said conveying means. 15

In testimony whereof I affix my signature 20 in presence of two witnesses.

EDWARD NELSON.
